By his Attorney,
Nelson W. Howard

UNITED STATES PATENT OFFICE

MILTON H. BALLARD, OF BEVERLY, MASSACHUSETTS, ASSIGNOR TO UNITED SHOE MACHINERY CORPORATION, OF PATERSON, NEW JERSEY, A CORPORATION OF NEW JERSEY

CLICKING MACHINE

Application filed March 1, 1930. Serial No. 432,451.

This invention relates to hand-wheel locking devices and is herein illustrated as embodied in a clicking machine of the type disclosed in United States Letters Patent No. 5 1,431,920, granted October 17, 1922 upon an application filed in my name.

Clicking machines of the type referred to commonly comprise a presser arm mounted upon a post which is arranged for reciprocation relatively to a cutting block in producing pressure-applying operations of the arm upon work positioned on the cutting block. The post is carried upon a shaft, upon which it is adjustable by means of a hand-wheel for 10 raising or lowering the post relatively to the shaft in order to adjust the position of the presser arm relatively to the cutting block.

An object of the invention is to provide in machines of the type referred to an improved locking device whereby relative movement of the post and shaft during the operation of the machine will be prevented.

To this end and as illustrated, there is provided in a clicking machine comprising a 25 shaft, a post mounted upon the shaft, and means for adjusting the position of the post along the shaft, a locking member for engaging the post and shaft for locking the post in adjusted position relatively to the shaft, together with means for normally urging the member into locking position, and means for 30 retracting said member to render it inoperative. As shown, the locking member comprises a detent rotatably and slidably carried by the post and arranged to be engaged in one or another of a plurality of holes in a hand-wheel operatively connected to the post for adjusting the post relatively to the shaft. Preferably the locking member is urged into 35 locking position by a spring and has associated with it a cam effective upon rotation of the locking member to withdraw it from locking position.

The construction set forth provides a comparatively simple and inexpensive device which operates to prevent relative movement of the hand-wheel and the post and consequently relative horizontal movement between the shaft and post due to vibration of 45 the machine during its operation. This obvi-

ates any change in the position of the presser arm with respect to the cutting block which would tend, for example, to force a die further into the cutting block than is desirable, but at the same time provides for adjustment of the presser arm for operation upon dies of 55 different heights.

Other objects and features of the invention will appear from the following detailed description and claims when taken in connection with the accompanying drawings, in which

Fig. 1 is a sectional view through the upper portions of the post and hand-wheel of a clicking machine embodying the invention;

Fig. 2 is a plan view of the upper portion of the post and associated parts; and

Fig. 3 is a side view showing details of the lower portions of the locking device.

Fig. 1 illustrates the upper portion of a clicking machine comprising a frame 10 having slidably mounted therein a hollow post 12 to which is rigidly connected a presser arm 14 overlying a cutting block 16. The post is supported for reciprocation in the frame by means of an upright shaft 18, the upper portion of which has a collar 20 upon which rests a bearing 22 supporting a screw-threaded sleeve 24 which makes connection with the upper end of the post 12. The sleeve 24 has a smooth end portion 26 upon which is mounted a hand-wheel 28 rigidly secured to the sleeve by a key 30. By means of the hand-wheel the sleeve 24 can be rotated relatively to the post 12 to raise or lower the latter with respect to the shaft 18, thereby to vary the height of the presser arm above the cutting block 16. The sleeve and hand-wheel are retained upon the shaft 18 by a split nut 32 screw-threaded on the upper end 34 of the shaft, the parts being adjusted to permit rotation of the post 12 and sleeve 24 relatively to the shaft in moving the presser arm 14 laterally over the bed 16. For further details of the construction and operation of the parts thus far described reference may be had to the aforementioned Letters Patent No. 1,431,920.

In order to prevent likelihood of relative turning movement between the sleeve 24 and

post 12 as a result of vibration, means is provided for locking the hand-wheel 28 to the post. To this end, the post is provided with a bracket 36 at the upper end of which is a 5 collar 38 positioned over the smooth portion 26 of the sleeve 24, the lower end of the bracket having a flanged portion 40 surrounding the upper part of the post 12 and being secured thereto by set-screws, one of 10 which is indicated by reference character 42. The bracket 36 has a projection 44 and a boss 46 in which is rotatably and slidably mounted a locking member or detent comprising a rod 48. The upper end of the rod 48 is adapted 15 to be inserted in one or another of holes 50, 52 (Figs. 1 and 2) in the hub 54 of the hand-wheel 28. It is to be noted that the holes 50 extend entirely through the hub 54 but that holes 52, which are located in portions of the 20 hub in alignment with spokes 55 of the hand-wheel, are in the form of recesses, thus to avoid weakening the spokes.

The rod 48 is provided with a spring 56, the 25 ends of which engage a pin 58 on the rod and the upper surface of the boss 46, tending normally to force the rod upwardly in the direction of the hub 54. The rod 48 is provided at its lower end with a projection 60 forming a handle by which the rod can be rotated. The handle 60 normally extends at 30 right angles to the axis of the post and is received in the V-shaped notch 62 in the boss 46. The side walls 64 of this notch form cam surfaces, best shown in Fig. 3, operative when 35 the handle 60 is turned outwardly in either direction to engage the handle and to force it and the rod downwardly. When the handle is turned outwardly about 45° it will pass out of the notch 62 and will be positioned beneath one of the lower surfaces 66 of the boss 46 and such surface will operate to engage the handle to lock the rod 48 in retracted position against the tension of the spring 56.

When it is desired to adjust the height of 45 the presser member, the handle 60 is turned outwardly until it is positioned beneath the boss 46 in which position the rod 48 is withdrawn from engagement with the hand-wheel 28. The hand-wheel is then rotated to obtain 50 the required relative movement between the post 12 and the shaft 18 in adjusting the height of the presser member 14 above the cutting bed 16. The handle 60 is then turned inwardly until it enters the V-shaped notch 55 62 whereupon the spring 56 will urge the rod 48 upwardly into engagement with the hub 54, and upon alignment of one of the holes 50, 52 with the axis of the rod, the spring 56 will force the rod into such hole, thereby 60 locking the hand-wheel to the post 12.

It should be noted that the holes 50, 52 are sufficiently close together that the maximum amount of movement of the hand-wheel required to bring a hole 50, 52 in alignment 65 with the rod 48 is very small, thereby render-

ing the locking device operable for fine adjustments of the post relatively to the shaft.

Having described my invention, what I claim as new and desire to secure by Letters Patent of the United States is:—

1. A clicking machine comprising a shaft, a post mounted upon the shaft, means for adjusting the position of the post along the shaft, a member carried by the post and adapted for engagement with the adjusting means for locking the post in adjusted position, means normally operative to urge the member into engagement with the adjusting means, and means for retracting the member to render it inoperative.

2. A clicking machine comprising a shaft, a post mounted upon the shaft, means for adjusting the position of the post along the shaft, a movable member for engaging the post and the adjusting means for locking the post in adjusted position, means for urging the member into locking position, means for retracting the member to render it inoperative, and means for locking the member in inoperative position.

3. A clicking machine comprising a cutting bed, a presser arm spaced from the bed, a hollow member for supporting the arm, a shaft for reciprocating the hollow member in producing pressure-applying operations of the arm upon the bed, and a manually operable member for adjusting the position of the hollow member relatively to the shaft, one of said members having therein a plurality of holes and a detent carried by the other of said members co-operable with one of the holes for locking the members in adjusted relation.

4. A clicking machine comprising a shaft, a post carried by the shaft, connections between the shaft and post including a hand-wheel for adjusting the post relatively to the shaft, the hand-wheel having holes therein, a detent carried by the post arranged for engagement in one of the holes for locking the hand-wheel to the shaft, means for urging the detent into locking position, and manually operable means for retracting the detent.

5. A clicking machine comprising a shaft, a post carried by the shaft, a hand-wheel for varying the relative position of the post with respect to the shaft and having therein a plurality of holes, a bracket secured to the post, a detent slidably mounted in the bracket for engagement within one or another of the holes in the hand-wheel to lock the hand-wheel to the post, a spring operative normally for urging the detent toward the hand-wheel, and a cam for retracting the detent.

6. A clicking machine comprising a shaft, a post mounted upon the shaft, a hand-wheel for adjusting the post relatively to the shaft and in which are located a plurality of holes,

- a bracket carried by the post, a detent rotatably and slidably mounted upon the bracket for co-operation with one or another of the holes in the hand-wheel to lock the hand-wheel to the post, the bracket having a cam surface, and a projection on the detent normally positioned in engagement with the cam surface and co-operable therewith to retract the detent upon rotation thereof.
- 10 7. A clicking machine comprising a shaft, a post adjustably mounted on the shaft, a hand-wheel for varying the position of the post relatively to the shaft and in which is located a plurality of holes, a bracket carried by the post, a detent rotatably and slidably mounted in the bracket and adapted to be positioned in one or another of the holes in the hand-wheel for locking the hand-wheel to the post, a spring operative normally to force 20 the detent into locking position, and a V-shaped notch in the bracket the walls of which are operative to withdraw the detent from locking position upon rotation thereof.
8. In a clicking machine, a sleeve, a post adjustably mounted on the sleeve, a hand-wheel for obtaining relative adjustment between the post and sleeve and having a plurality of openings therein, a bracket carried by the post, a detent rotatably and slidably 30 mounted in the bracket and arranged to be positioned in one or another of the openings in the hand-wheel, a spring for urging the locking member toward the hand-wheel, the bracket having a V-shaped notch, and a projection on the locking member normally positioned in the V-shaped notch and arranged to co-operate with the walls of the notch to retract the detent upon rotation thereof.
- In testimony whereof I have signed my 40 name to this specification.

MILTON H. BALLARD.
